UNITED STATES PATENT OFFICE.

ARPAD RÓNAY, OF BERLIN, GERMANY, ASSIGNOR, BY MESNE ASSIGNMENTS, TO
GENERAL BRIQUETTING CO., OF NEW YORK, N. Y., A CORPORATION OF MAINE.

PRESS.

1,099,667.

Specification of Letters Patent. Patented June 9, 1914.

Application filed July 27, 1910. Serial No. 574,031.

To all whom it may concern:

Be it known that I, ARPÁD RÓNAY, a subject of the King of Hungary, and residing at Berlin, Germany, have invented certain new and useful Improvements in Presses, of which the following is a specification.

My invention relates to presses for making briquets, and a primary object is to provide a press, all the faces of whose mold are formed by movable stamps or rams which operate either together or in an optional order in succession. This pressure action on all sides enables the air to be removed from the briquet material particularly effectively.

One special form of my invention is characterized by the displaceable or rotating mold table, which is well-known *per se*, being employed as the bottom limiting face instead of the lower stamp being so employed, so that the briquet material can be preliminarily pressed in the mold which is formed exclusively by the stamps; the material preliminarily pressed in this manner is finally pressed in well-known manner in the mold table itself after transference into a mold provided in known manner in the latter.

The press can be particularly advantageously employed for briquetting coal. Namely, it has been found that the coal coming from the drying chamber or stove at a temperature of over 100° C., particularly when it is in a loose condition, loses part of its capability of binding when it comes into contact with the open air before it is finally or at least preliminarily pressed. My invention affords the possibility of coal which is conveyed from the drying chamber directly into a suitably-shaped feed chamber being exposed to pressure on all sides without coming into contact with the open air; it may here be a matter of pressing the material preliminarily or finally.

Another material advantage attaching to the subject-matter of my invention consists in the same enabling perfectly dust-free pressure, so that the production of dust which is otherwise unavoidable in the case of various materials is impossible.

Several illustrative embodiments of my invention are represented by way of example in the accompanying drawing, wherein:—

Figure 1 is a vertical longitudinal section showing a press in which all the walls of

the mold are formed by movable stamps; Figs. 2 to 5 show a second embodiment in combination with a rotary table, namely Fig. 2 is a vertical longitudinal section showing the parts in their position during the filling operation, Fig. 3 a horizontal section in the plane A—B in Fig. 2, Fig. 4 shows the position of the parts when the preliminary pressing operation is complete, and Fig. 5 is a horizontal section in the plane C—D in Fig. 4, while Fig. 6 is a horizontal section showing another modified form of the movable walls.

Referring firstly to Fig. 1, the material to be pressed is fed into a chamber *a* through the flanged tubular chute *b*. When coal is being briquetted the chute *b* is connected directly with the drying chamber by a pipe. The walls of the chamber *a* are formed so that six stamps or rams can move in the same, namely two vertical rams *c*, two horizontal rams *d* moving in the plane of the drawing and two rams *e* moving at right angles to this plane, and the ends of these rams form the walls of the mold. In this illustrative embodiment the rams are of rectangular section and the pressing faces thereof are plane; I may however form them otherwise, for example calotte-shaped, in which event the material is pressed for example into the form of a sphere.

The press illustrated in Fig. 1 is operated by material to be pressed being fed intermittently or continuously through the chute *b*, while the stamps *c*, *d*, *e* simultaneously move outward and inward and during the latter motion briquet the material which is located between their pressing faces in the manner readily understood from Fig. 1. The mode of operation of the press according to Fig. 1 may however be modified by employing the subject-matters of my United States patent applications Serial Nos. 508,783 and 508,784 filed July 21, 1909. In this event only the four horizontal stamps *d*, *e* would at first move toward one another and preliminarily press the material; then the two vertical stamps *c* would operate, the horizontal stamps *d*, *e*, which are securely held in the meantime, acting as sliding molds.

In order to do this, however, the feed box or chamber *a* would have to be displaceable vertically with the stamps *d*, *e*, which would necessitate the chute *b* being connected with a flexible pipe. The process

described in my former applications referred to above could, however, also be employed if the vertical walls of the feed box *a* were formed of several parts in such manner that 5 one part can be displaced relatively to the others. Instead of using the vertical stamps *e*, *e* for the mode of pressing described in the applications referred to above, one of the pairs of stamps *d*, *d* or *e*, *e* may be employed for the same purpose. The construction of the feed box *a* or its mounting would then have to be modified correspondingly.

In the illustrative embodiment according to Figs. 2 to 5 the subject-matter of my invention is used in combination with a mold table *i*, rotating in well-known manner, whose molds *l* are alternately filled and emptied again during one revolution of the table. The movable stamps *f* of the embodiment according to Figs. 2 to 5 act, in combination with the mold table *i*, as a preliminary press, while the real or final pressure is brought about by the ram *h* and the counter-ram *k*.

The illustrative embodiments shown in 25 Figs. 2 to 5 comprise only two horizontally displaceable preliminary pressure stamps *f*, whose operative faces *g* are formed semi-circular, so that these surfaces form a complete cylinder when the stamps contact one another, as shown in Fig. 5. The operative faces *g* may, however, be made angular as shown in Fig. 6, so that when the stamps contact one another a die of square section is inclosed by the same.

35 The mode of operation of the illustrative embodiments according to Figs. 2 to 5 and Fig. 6 is such that in the position according to Fig. 2 the mold *g* is filled in the direction of the arrows. This filling is brought about, 40 for example, as in the illustrative embodiment shown in Fig. 1, by means of a closed receptacle *a* which may be connected with a drying chamber or the like. The two lateral rams *f* occupy the relative positions 45 shown in Figs. 2 and 3 while the vertical ram *h* is located in its uppermost position. The two rams *f* then approach one another until they occupy the position shown in Figs. 4 and 5; during this time the mold table *i* 50 has rotated so that its mold *l* is located under the ram *h* and under the briquet mass surrounded by the rams *f*. While the table is securely held the top stamp *h* presses the preliminarily formed briquet from the mold *g* 55 into the mold *l*, the stamp *h* acting as counterstamp. The arrangement may, however, be such that the rotating mold table *i* is omitted. The top stamp *h* then becomes op-

erative as soon as the rams *f* occupy the position shown in Figs. 4 and 5. The top face of 60 the counter-ram *k* here limits the bottom side of the mold *g*. The bottom stamp *h* may act in like manner as the pressing stamp proper, the top stamp *h* being formed as counter-stamp. Lastly, both stamps may 65 operate simultaneously.

Obviously, the briquetting process disclosed in the applications referred to above may likewise be employed in connection with the illustrative embodiment shown in Figs. 2 to 70 5 and Fig. 6 both with and without the rotary mold table *i*.

Those stamps which are formed as preliminary pressure rams may be provided with 75 perforations or ducts opening into the atmosphere in order to accelerate the removal of the air. In order to prevent these passages becoming stopped up pins may project into the same in such manner that when the rams, *e. g.*, *f*, move outward these pins clean 80 the passages.

I claim:—

1. In a press of the type described, the combination of a feed chamber, and stamps movable in the walls of the chamber, the inner ends of the stamps in their innermost position forming a mold in the chamber, said stamps being adapted to move away from and toward one another.

2. In a press of the type described, the combination of a mold table, a feed chamber on the mold table, stamps movable in the walls of the chamber, the inner ends of the stamps in their innermost position forming a preliminary mold in the chamber, a top vertical stamp movable in the top wall of the chamber, and a bottom stamp at the mold table, said stamps being adapted to move away from and toward one another.

3. In a press of the type described, the combination of a feed chamber, and stamps movable in the walls of the chamber, the inner ends of the stamps in their innermost position forming a mold in the chamber, said stamps being adapted to move away from and toward one another, said feed chamber being closed and supplying material to be pressed to the mold formed by the stamps, atmospheric air being thereby excluded from the material.

In testimony whereof, I affix my signature in the presence of two witnesses.

ARPAD RÓNAY.
